FOREIGN PATENT DOCUMENTS

WO 2014005225 1/2014

Primary Examiner — Mark Goodwin(74) *Attorney, Agent, or Firm* — Lynn C. Schumacher; Stephen W. Leonard; Hill & Schumacher(57) **CLAIM**

The ornamental design for a fiducial marker support, as shown and described.

DESCRIPTION

FIG. 1 is a perspective view of one embodiment of a fiducial marker support showing our new design incorporated into a longitudinal axis tool;

FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof; and,

FIG. 7 is a rear elevational view thereof.

The broken lines shown in the figures are included for the purpose of illustrating portions of the fiducial marker support and form no part of the claimed design.

1 Claim, 3 Drawing Sheets(56)
